DESIGN FOR A COMBINED EVENING AND STREET DRESS

Sylvester Fusco, New York, N. Y.

Application October 9, 1939, Serial No. 87,571

Term of patent 3½ years

To all whom it may concern:

Be it known that I, Sylvester Fusco, a citizen of the United States, residing in New York city, in the county of New York and State of New York, have invented a new, original, and ornamental Design for a Combined Evening and Street dress, of which the following is a specification, reference being had to the accompanying drawings, forming part thereof.

Fig. 1 is a front view of a combined evening and street dress showing my design;

Fig. 2 is the back view of Fig. 1;

Fig. 3 illustrates the front view of Fig. 1 with the lower skirt portion thereof omitted, and

Fig. 4 illustrates Fig. 1 with the upper skirt portion forming tunic omitted.

I claim:

The ornamental design for a combined evening and street dress, substantially as shown.

SYLVESTER FUSCO.
